G. A. CARLSON

HASP

Filed May 27, 1922

Inventor:
Gustav A. Carlson
By Dyrup, Jr., Chittenden, Miles,
Atty.

UNITED STATES PATENT OFFICE.

GUSTAV A. CARLSON, OF CHICAGO, ILLINOIS, ASSIGNOR TO THE BOYE NEEDLE COMPANY, OF CHICAGO, ILLINOIS, A CORPORATION OF ILLINOIS.

HASP.

Application filed May 27, 1922. Serial No. 564,027.

To all whom it may concern:

Be it known that I, GUSTAV A. CARLSON, a citizen of the United States, residing at Chicago, in the county of Cook and State 5 of Illinois, have invented a new and useful Improvement in Hasps, of which the following is a specification.

This invention relates particularly to hasps for use in connection with barn doors 10 or the like.

The primary object is to provide a thoroughly durable and secure device of this character of exceedingly simple construction which can be manufactured very cheaply.

15 A further object is to provide such a hasp which is reversible, so that "rights" and "lefts" are not required.

The invention is illustrated in its preferred embodiment in the accompanying 20 drawing, in which—

Fig. 1 represents a broken perspective view of a door and door-frame equipped with the improved hasp; Fig. 2, a broken 25 sectional view showing the door in closed position, the section being taken as indicated at line 2 of Fig. 1; Fig. 3, a broken vertical sectional view taken as indicated at line 3 of Fig. 2; and Fig. 4, a broken edge elevational view of the door-frame, showing 30 the keeper in elevation.

In the construction illustrated, A represents a door; A' a door-frame or post; B, a keeper secured to the member A'; and C, a latch device secured to the door and 35 acting with the keeper B.

The keeper B comprises a small sheet-metal plate having a base portion 1 provided with screw-receiving perforations and having projecting from the base portion and 40 substantially at right angles thereto a padlock loop 1^a. The keeper is formed by punching and shearing the metal suitably and bending the loop which is thus provided so that it will project outwardly from the base portion. The loop has the opening 45 2 for receiving the padlock. The loop also has a rounded outer edge 1^b on which the latch member is adapted to ride when the door is swung to the closed position. At 50 the base of the upper member of the loop is a notch or latching recess 1^c which is formed by suitably notching the upper edge portion of the loop of the keeper, prior to the bending operation.

55 The punching and stamping operation is

so performed that the base is provided with a central projecting ear 1^d whose base portion is disposed between the base portions of the members of the loop.

The latch device C comprises a mounting plate 3 and a latch-plate 4 which is pivotally connected therewith by means of a rivet 5. The mounting plate 3 is provided with perforations which receive screws 6, by means of which the mounting plate is securely fastened to the door. The keeper B is secured to the door jamb or frame by means of screws 7, one of which passes through the central ear 1^d and the others of which pass through end portions of the main part of the base which is disposed on the opposite side of the loop.

In mounting the latch device the mounting-plate 3 preferably projects slightly beyond the free edge of the door, as shown 75 in Fig. 1. At the projecting end of the plate 3, a small outturned central lug 8 is provided. This lug works in a vertical slot 9 with which the latch-plate 4 is provided, so that the latch-plate will be supported in 80 the position shown in Fig. 1, but will be free to rise when the latch rides over the keeper.

The latch-plate 4 is further provided with a projecting end portion 4^a which has there- 85 in a vertical slot 10 which is adapted to embrace the loop 1^a of the keeper. When the door is swung to the closed position, the upper end wall of the slot 10 rides on the curved outer edge of the loop 1^a and drops 90 into the notch 1^c. When the door is in the closed position, with the slot 10 receiving the loop of the keeper, a padlock may be inserted through the loop.

The mounting-plate 3 is secured to the 95 door before the latch-plate is swung to a position substantially parallel with the mounting-plate. The lock 8 projects only a small distance from the outer surface of the mounting-plate, so that the latch-plate 100 4 may be forced over the lock, the latch-plate springing sufficiently to permit this to be accomplished. The lock 8 will then serve as a stop, limiting the downward swing of the latch-plate with relation to the 105 mounting-plate.

The latch-plate 4 is equipped with a finger piece or handle 11, the stem 11^a of which extends freely through a slot 12 in the mounting-plate 3 and through a perfora- 110

tion in the door. Thus, the latch may be lifted from either side of the door. The stem portion of the finger piece 11 is driven tightly into a perforation or small slot with 5 which the latch-plate 4 is provided.

The improved device, by reason of the fact that it is formed from sheet-metal, the members lying for the most part in a single plane, can be cheaply manufactured, read- 10 ily assembled, and shipped in very compact form. It will be understood that the finger piece may be driven through the latch-plate 4 after the latch device has been applied to the door. The screws 6 of the mounting- 15 plate are covered by the latch-plate; and the screws 7 of the keeper are also covered by the projecting end of the latch-plate, so that when the latch-plate is locked to the loop of the keeper by means of a padlock, 20 the door is securely fastened and the screws can not be removed.

The latch device may be used at either vertical edge of the door and the same is true of the keeper. If, for any reason, it is 25 desired to use the device in such manner that it will not latch, the keeper may be reversed and the rounded lower outer edge of the keeper will then afford a surface on which the upper wall of the slot 10 can ride 30 when the door is closed, but the door will not be latched. This is sometimes desirable where a spring is employed for closing the door and the door is to be opened frequently.

The improved construction is simple, can 35 be manufactured very cheaply, and is thoroughly effective for its purpose.

What I regard as new, and desire to se-
sure by Letters Patent, is—

1. A device of the character set forth, comprising a sheet-metal keeper punched, 40 sheared, and bent and affording a base por-
tion provided with a projecting central
screw-receiving ear and a padlock loop pro-
jecting at right angles to the base portion,
the base portions of said loop flanking the 45
base portion of said ear and the upper edge
of said loop being provided with a recess;
and a pivotally mounted latch-engaging
member having its free end portion provided
with a transverse slot adapted to receive, 50
said padlock loop, the end wall of said slot
serving to latchingly engage the recess of
said keeper.

2. A device of the character set forth
comprising a sheet-metal keeper punched, 55
sheared and bent and affording an attaching
base provided with a central projecting ear
and a padlock loop whose base-portions
flank said ear, said loop having its upper
edge provided at its base portion with a 60
latch-engaging recess; and a coacting latch-
device comprising a mounting-plate, a latch-
plate pivotally connected with said mount-
ing-plate and having a projecting end por-
tion provided with a transverse slot whose 65
upper end wall is adapted to ride on the
loop of said keeper and latchingly engage
the recess at the base of said keeper, and a
finger piece secured to said latch-plate and
extending freely through an opening in said 70
mounting-plate.

GUSTAV A. CARLSON.
